US0D1076960S

(12) **United States Design Patent** (10) **Patent No.:** **US D1,076,960 S**
 (45) **Date of Patent:** **** May 27, 2025**

(54) **DISPLAY SCREEN WITH GRAPHICAL USER INTERFACE**

(71) Applicant: **HME, Incorporated**, Wyoming, MI (US)

(72) Inventor: **Kenneth C. Lenz, Jr.**, Hudsonville, MI (US)

(73) Assignee: **HME, Incorporated**, Wyoming, MI (US)

(**) Term: **15 Years**

(21) Appl. No.: **29/822,295**

(22) Filed: **Jan. 28, 2022**

Related U.S. Application Data

(62) Division of application No. 29/730,353, filed on Apr. 3, 2020, now abandoned, which is a division of application No. 29/653,206, filed on Jun. 13, 2018, now Pat. No. Des. 884,010.
